CLAIM

The ornamental design for a decorative sleeve for spray bottle, as shown and described.

DESCRIPTION

FIG. 1 is a perspective view of a decorative sleeve for spray bottle showing my new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view thereof; and,

FIG. 8 is a perspective view thereof with an illustration of the environment of fitting with a spray bottle.

The broken lines in FIGS. 1–3 and 6–8 depict portions that represent environment and form no part of the claimed design.
